UNITED STATES PATENT OFFICE.

RICHARD DUANE GREEN, OF TRENTON, NEW JERSEY, ASSIGNOR TO JOHN A. ROEBLING SONS COMPANY, A CORPORATION OF NEW JERSEY.

WIRE ROPE.

1,382,723.

Specification of Letters Patent. Patented June 28, 1921.

Application filed August 26, 1919. Serial No. 319,923.

To all whom it may concern:

Be it known that I, RICHARD DUANE GREEN, a citizen of the United States, residing at Trenton, county of Mercer, and State 5 of New Jersey, have invented certain new and useful Improvements in Wire Rope, fully described and represented in the following specification and the accompanying drawings, forming a part of the same.

10 This invention relates to the provision of an improved core for wire ropes, and especially for hoisting or similar sheave use where great flexibility is required. These ropes have usually been formed by laying 15 a plurality of wires or strands about a central strand of manila or like fiber.

The especial object of the present invention is the provision of a cheap, strong and easily manufactured core construction adapted to take the place of the more expensive manila cores.

20 In the accompanying drawings forming part of the specification there is shown for the purpose of illustration a core of the preferred form embodying all the features of the invention, and this construction will now be described in detail and the features forming the invention then specifically pointed out in the claims.

30 In the drawings,—

Figure 1 is a plan view of a rope having one layer of strands with one end of the rope strands broken away and some of the disks separated to show the core construction; and

35 Fig. 2 is a cross section of the rope.

Referring to the drawings, A is a suitable central wire or support on which a plurality of comparatively thin disks B, formed of 40 fiber, leather or other cheap material of such strength as to support the pressure of the wires and of sufficient diameter to equal

that desired for the core, are loosely assembled by being strung side by side. These disks form the rope core, and the rope strands C composed of small wires are laid thereon in the usual manner.

This construction provides a cheap and satisfactory substitute for the manila cores now used and the loose bearing of the disks 45 B against each other gives the flexibility desired and acts very efficiently to retain lubricant. In some instances it may be found desirable to remove the small central wire or support A after the formation of the 50 rope, and the central passage thus formed provides convenient means for the passage of lubricant to the spaces between the disks.

While the invention is shown and described in connection with a rope formed 55 of strands consisting of a plurality of small wires, as usual in wire rope constructions, it will be understood that the invention is not so limited as the same is adapted for uses in which the strands are of single wires. 60 It will be understood, also, that the invention is not limited to constructions in which the rope strands are laid directly on the disk core, but that the rope may be built up 65 on the core in any usual or suitable manner. 70

What I claim is:

1. A wire rope having a core comprising a plurality of disks, substantially as described.

2. A wire rope having a core formed by a 75 small central support and a plurality of disks strung thereon, substantially as described.

3. A wire rope core comprising a central wire and a plurality of disks loosely strung 80 on the wire, substantially as described.

In testimony whereof, I have hereunto set my hand.

RICHARD DUANE GREEN.
